Pierce, P.L.C.

(57) **CLAIM**

The ornamental design for a base part for an electronic
vaping device, as shown and described.

DESCRIPTION

FIG. 1 is a front-top perspective view of a base part for an
electronic vaping device;

FIG. 2 is a front view of the base part for an electronic
vaping device shown in FIG. 1;

FIG. 3 is a rear view of the base part for an electronic vaping
device shown in FIG. 1;

FIG. 4 is a left side view of the base part for an electronic
vaping device shown in FIG. 1;

FIG. 5 is a right side view of the base part for an electronic
vaping device shown in FIG. 1;

FIG. 6 is a top view of the base part for an electronic vaping
device shown in FIG. 1;

FIG. 7 is a bottom view of the base part for an electronic
vaping device shown in FIG. 1; and,

FIG. 8 is a rear-bottom perspective view of the base part for
an electronic vaping device shown in FIG. 1.

The evenly spaced broken lines in the drawings depict
portions of the base part for an electronic vaping device that
form no part of the claimed design.

1 Claim, 8 Drawing Sheets
